UNITED STATES PATENT OFFICE.

ASA FRED BATCHELDER, OF SCHENECTADY, NEW YORK, ASSIGNOR TO
THE GENERAL ELECTRIC COMPANY, OF NEW YORK.

ARMATURE WINDING AND COIL.

SPECIFICATION forming part of Letters Patent No. 596,136, dated December 28, 1897.

Application filed September 15, 1897. Serial No. 651,732. (No model.)

To all whom it may concern:

Be it known that I, ASA FRED BATCHELDER, a citizen of the United States, residing at Schenectady, in the county of Schenectady, 5 State of New York, have invented certain new and useful Improvements in Armature Windings and Coils, (Case No. 620,) of which the following is a specification.

My present invention relates to the windings of armatures for dynamo-electric machinery. While it might be usefully applied to generators, it is not of so much importance in them, because in general considerable room may be taken without inconvenience for this 15 class of apparatus, rendering it unnecessary to consider many problems of this nature which arise with motors. In these, and more particularly with railway-motors to which my invention applies with perhaps its greatest 20 utility, space is of the greatest importance. In railway apparatus carried under a car the length of the motor is limited by the gage, and, in fact, by the length of that part of the axle between the inner surfaces of the wheels. 25 The armature is further limited not only in length by the dimension named, (which is reduced still more by the space needed for the commutator and bearings,) but in diameter by the height of the car-sills above the rail, 30 which in a tram-car particularly must not be too great. Notwithstanding these limits modern conditions demand continued increase in output of railway-motors, together with lower price. To some extent at least to meet this 35 demand is the occasion of my present invention, which has for its object to devise a winding composed of interchangeable detachable coils separately wound and insulated before being applied to the core. Each of these coils 40 is in turn composed of a number of separate insulated wires of one or more turns, according to the voltage and output required, so that each coil applied as a unit to the armature-core is in reality composed of a plurality 45 of coils, each having its own part in the generation of electromotive force and independent of one another, except, of course, so far as their unavoidable mutual inductance is concerned. This part of my invention enables 50 me to produce a winding which shall have the increased output desired with a saving of la-

bor and consequent lower cost, inasmuch as the two, three, or more wires comprising the coil are all wound at one time and by one operation.

Another part of my invention consists in the conformation and adaptation of my improved armature-coils to cores limited in size by the considerations already mentioned.

Prior motor-armatures built in recent years 60 have had a winding made up of counterpart coils of equal length and inductive effect, having sides lying in the armature-slots. One side of each coil lies in the bottom of an appropriate slot, and the other side of the same 65 coil lies in the upper portion of its slot, resting upon the lower sides of other coils. With such an arrangement the various coils can be counterparts in length and can be readily applied and removed from the core. In wind- 70 ings of this type the end portions of the coils have been given an offset at or near a central point, separating the end portions into parts forming an inside and outside series when in place on the core. Two or three modified 75 ways of arranging the end connections have been employed. In some of these the connections are bent in toward the shaft, so that they lie against the head of the core in planes transverse or approximately trans- 80 verse to the armature-shaft. In others the end connections have been arranged in arcs following the outer circumference of the core, and the offset stands practically radial with the shaft. In others the end connections form 85 chords across the arc spanned by the sides of the coil.

The first-named winding is made in several ways, all, however, employing counterpart coils having long and short sides in the armature-slots, with curved or bent connecting-wires so arranged that one part of a coil overlies the other part of another coil, the curved parts being bent down over the armature-head and being "offset" at a point in the 90 curve. The core to which this winding is applied must be of a certain diameter large enough to accommodate the winding. The wires at the offset in the coil take considerable space, and the size of circle occupied by 100 the offsets forms the inside limit of the winding. Outside of this the core must be of suf-

ficient size to accommodate the coils, so that it has a limit of diameter determined mainly by the space needed for the offsets and end portions of the coils, below which it cannot go with this form of winding, though it may be of almost any desired shortness parallel to the shaft.

In another form of the winding above named—namely, that one in which the end connections form chords across the arc spanned by the sides of the coil—the diameter of the armature may be almost anything desired within reason; but this advantage is obtained by unduly increasing the length of the armature, and particularly of that part of the armature which contributes no useful result electrically—namely, the part occupied by the end connections. This is what is known as the “barrel-winding,” although it is in reality simply another form of the winding first described.

The winding which I have devised occupies a place intermediate of the two described, and in it I have endeavored to combine the advantages of both without incurring the difficulties attendant upon the use of either.

In my invention I employ a coil having the two sides designed to generate electromotive force occupying slots in the armature-periphery. These two sides may be connected at one end of the coil by end portions, like those of the barrel-winding, slightly turned down over the armature-head. At the other end of the coil the two sides are joined by end portions which may be considered as composed of three parts, one of which is offset from its neighbor, the two being of nearly equal length. The first part passes in an involute curve from the armature-slot to the interior limiting-circle of the winding, where an offset is made, so that the second part returns outside of the first part of preceding coils until it reaches the exterior circle marking the periphery of the armature-core, but longitudinally displaced from it. Here a bend is made, and the third short part passes in what may be called a portion of a screw-thread back to the top of the slot. One of the sides of each coil lies in the bottom of one slot, while the other is in the top of another slot located at the proper polar point around the armature.

The solution of the mechanical side of the armature-winding problem indicated above is practically a general one, at least if the coil end be considered as a series of lines—that is, having an inner cylinder of a given circumference (determined by the space required for the coil offsets) and a concentric outer cylinder of a circumference determined by the teeth and coil-slots of the armature-face, it is always possible to span a given polar pitch or angle from one to the other by two involute curves and a spiral, one of the involutes being offset from the other. While I have described this construction as applied to one end of the coil, where it is desired to still further shorten the armature, it will be

useful to employ it at both ends. I have described and illustrated both constructions and aim to include both in my claims. 70

The drawings annexed show my invention applied to a four-pole motor-armature.

Figure 1 is a perspective of an armature-core having some of the coils applied. I have only illustrated enough to exhibit the construction, as the complete figure would be more obscure. Figs. 2 and 3 are perspective views of the coil in different positions. Fig. 4 is a plan of a coil, with a modification shown in dotted lines. Fig. 5 is an end elevation of the armature-core with some of the coils in place. Fig. 6 is a corresponding view of the other end of the armature core and coils. Figs. 7, 8, and 9 are sectional views in detail, respectively illustrating the barrel-winding, 85 the drum-winding, and the winding of the present invention.

I will first describe my invention in relation to Fig. 4 of the drawings, in which a coil embodying it is shown in plan. In all of the 90 drawings the coil is lettered B. The parts contained in the slots of the armature are lettered b b. At one end of the coil they are shown in this figure as joined by two end portions b⁵ b⁷, offset from one another at the point b⁶. So far as this end of the coil is concerned it is similar to the ordinary so-called “barrel-winding.” At the other end of the coil the sides b b are joined by the peculiar connection of my invention, consisting of two 100 involute curves b' b', offset from one another at b³. The part b' is joined to one of the sides of the coil occupying the armature-slot by a spiral b², the wires being bent at b⁸ b⁹ to complete this junction. In this same figure I 105 have shown, as already outlined in the statement of invention, that my invention may be applied to both ends of the coil. The dotted lines in Fig. 4 sufficiently indicate how this may be accomplished and also show the 110 saving in length over the barrel-winding indicated in that figure. It will be unnecessary to further describe this modification, as it will be easily understood.

In Figs. 2 and 3 I show perspectives of my 115 improved coil in two different positions. The parts of the coil are lettered as in Fig. 4, and its construction will be readily understood from these figures.

I will next refer to Fig. 6, which shows an 120 end elevation of the armature-core A, having some of the coils of my invention applied thereto. In this the dotted circle D shows the limiting-circle of the offsets b³ of the coils. The parts of the coil are lettered as 125 in Fig. 4. Being in end elevation, the two involutes b' b' and the spiral b² will be easily perceived.

In Fig. 1 I show the armature-core A in perspective with a number of the coils of my 130 invention applied to it. In the lower right-hand coil all of the parts do not appear, because the part b' here passes under the coils shown; but the construction of the winding

is clear, part of the coils being omitted, so that the part *b*, lying in the bottom of the slot, can be distinguished from the corresponding part *b*, which lies in the top of the slot.

5 In Fig. 5 I show in end elevation the opposite end of the armature, to which the barrel-winding is applied, as illustrating the difference between this winding and that of my invention.

10 Figs. 7, 8, and 9 serve to exemplify some of the advantages of the coil of my invention over others with which I am acquainted.

Fig. 7 illustrates the barrel-winding, *A* being the armature-core, and the end of the coil 15 being shown at *B'*. Under the coil end is the usual support *C*.

Fig. 8 shows the other form of counterpart coil now well known and referred to in my statement of invention. The end of the coil 20 is shown at *B*² and its support at *C*.

In Fig. 9 I show the coil end of my invention, the parts being lettered as before. In this figure the line *x'* shows the distance to which the winding shown in Fig. 7 would extend. Line *y'* shows the diameter of armature-core required to accommodate the winding shown in Fig. 8. The distance *x x'* is that saved by my invention over the winding shown in Fig. 7, while *y y'* shows that saved 30 over the winding shown in Fig. 8.

The distinguishing feature of my invention consists, therefore, in a coil having two sides carried in the slots of the armature, these two sides being joined either at one or at both 35 ends by three-part end connections, two at least of which are offset from one another. For the outline of the three end parts of the coil named I prefer two involute curves and a spiral for the reasons already set out; but 40 other lines might be employed without departing from my invention.

What I claim as new, and desire to secure by Letters Patent of the United States, is—

1. A coil for a dynamo-electric armature, 45 having the sides to be disposed on the armature-face united at least at one end by three end portions, two of which are involutes offset from one another, and the third a spiral.

2. A coil for a dynamo-electric armature, 50 having two parallel sides, the two sides united at one or at both ends by three end portions,

two of which are involute curves offset from each other at their joined ends, and the third a spiral joining one end of an involute to one of the parallel sides of the coil.

55

3. An armature-winding composed of detachable coils having offset end connections shaped to fit down over the armature-head, and occupying a space on the head bounded by an inner circle, at the circumference of which the offsets are arranged, and by the periphery of the armature-core, and extending for a certain distance approximately concentric with the periphery of the core, whereby the span between the sides of the coil is 60 greater than the span between the outer ends of the inwardly and outwardly extending portions of the coil ends.

4. An armature-winding consisting of detachable coils having end connections which 70 are in part shaped to fit over the head of the core, forming an inside and outside series in planes approximately transverse to the shaft, and in part shaped to lie in short arcs or chords in paths concentric, or approximately concentric, with the shaft and core.

5. In a dynamo-electric machine, an armature-winding made up of detachable counterpart coils having at their ends a part extending inward toward the shaft to an offset, a second portion extending outward from the offset to or near the circumference of the core, and another portion extending in an arc or chord to the desired polar point occupied by the side of the coil, as set forth.

85

6. An armature-coil having end portions shaped to form two involutes extending a certain distance inward toward the shaft, and then outward from the shaft, an offset joining the inner ends of said involutes, and a 90 third portion forming a continuation of the outer end of one of the involutes to the corresponding side of the coil, whereby the two sides of the coil are at unequal distances from the offset, as set forth.

95

In witness whereof I have hereunto set my hand this 13th day of September, 1897.

ASA FRED BATCHELDER.
